UNITED STATES PATENT OFFICE.

WALTER S. ADAMS, OF PHILADELPHIA, PENNSYLVANIA, ASSIGNOR TO THE J. G. BRILL CO., OF PHILADELPHIA, PENNSYLVANIA, A CORPORATION OF PENNSYLVANIA.

CAR-TRUCK.

1,162,201.

Specification of Letters Patent. Patented Nov. 30, 1915.

Application filed January 21, 1915. Serial No. 3,459.

To all whom it may concern:

Be it known that I, WALTER S. ADAMS, a citizen of the United States, and a resident of the city and county of Philadelphia and 5 State of Pennsylvania, have invented certain new and useful Improvements in Car-Trucks, of which the following is a specification.

This invention relates to a bolster supporting means in car trucks wherein the bolster is supported near each of its ends by a combination of leaf and coil springs, this combination allowing the bolster to be carried true without undue jar or vibration.

15 My invention also relates to bolster guides and dampers which eliminate the necessity of using chafing plates between the truck bolster and truck transoms, the bolster being prevented from coming into contact with 20 the transoms by other means, and also prevent the excessive swing of the bolster, but not prevent it from moving from one position to another as may be required by the conditions of service.

25 The present invention also resides in certain novel features of construction and combination of elements, which will be herein-after described and further pointed out in the claims appended hereto.

30 For a more particular description of my invention, reference is to be had to the accompanying drawings, in which—

Figure 1 is a side elevation of a truck provided with my improvements, the truck portions of the truck to which my invention has 35 no relation being shown in dotted lines; Fig. 2 is an end elevation of a portion of a truck provided with my improvements; Fig. 3 is a plan view of a portion of a truck provided 40 with my improvements; Fig. 4 is a sectional view of one of the pins and surrounding parts for holding the bolster guide and dampers; Fig. 5 is a sectional view on the line 5—5 of Fig. 3, looking in the direction of 45 the arrows; Fig. 6 is a perspective view of the bracket secured to the bolster; and Fig. 7 is a sectional view on the line 7—7 of Fig. 6, looking in the direction of the arrows.

I have indicated in a general way a truck 50 of any suitable type, (the same being shown in dotted lines throughout the drawings) comprising wheels 1, equalizing bars 2 and a top chord 3. Secured to the top chord 3 are transoms 4 and gusset plates 5. Mounted 55 on one of the gusset plates is a bracket 7 for

holding a release spring 8 for the brakes, not shown.

The bolster 9, which is shown in dotted lines in the drawing, is mounted upon a spring arrangement which will be described 60 below, and this spring arrangement is mounted upon a spring plank 10 which is supported by hangers 11 extending upward to the truck frame, where they are suitably supported. The lower ends of these hangers 65 11 are preferably perforated with square holes which fit snug on the square ends of the swing link pin 12. The center portion of this pin 12 is circular in cross section, the square parts being at each end and extending from said squared parts are threaded portions 13, upon one of which is a washer 14 and a nut 15 and on the other, a coil spring 16, cap 17 and nut 18.

The spring arrangement upon which the 75 truck bolster is mounted comprises a lower set of leaf springs 19, and an upper set of leaf springs 20, each set of leaf springs comprising three, although any number may be used if desired. Each leaf spring is held 80 together by a band 21. Mounted between the ends of the leaf springs are sets of coil springs, inner springs 22 and outer springs 23, the springs 22 being nested within the springs 23, there being four of these sets of 85 coil springs to each set of leaf springs, that is, two at each end of the leaf springs. The coil springs are mounted in seats 24 and each of said seats have cylindrical projections 25 and 26, the projections 25 moving within 90 the projections 26. Each of said seats also has a series of projections 27 on its outer side, these projections entering perforations 28 in the leaf springs 19 and 20.

When a predetermined weight, or number 95 of passengers is on the car, the coil springs 19 and 20 compress sufficiently to allow seats 24 to move toward one another, so that the upper ends of the projections 25 bear against the inner side of the upper seat and the 100 lower end of the projections 26 rest on the inner side of the lower seat, the seats being seated metal to metal, any additional load being carried by the leaf springs. The coil spring seats 24 are also slightly beveled as at 105 29 at their inner ends, so that when the coil springs are compressed and the seats bear against one another the leaf springs are supported on these beveled ends 29 of the seats 24. When thus supported, the operative 110

length of the leaf springs is lessened and they thus become stronger and their resistance to the weight of the load is increased.

Mounted on one of the gusset plates is a bracket 30 said bracket having a perforated portion 31. Mounted on the bolster 9 is a bracket 32 having a cylindrical portion 33, said portion being strengthened by vertical and horizontal webs 34 and 35, and having a perforation 36 extending through it, said perforation having a widened portion 37 at its center. Fitted within said perforation 36 and also within a perforation in the bracket 30 are pins 38 having widened portions 39, this portion on one of said pins fitting within the widened portion 37 of the perforation 36. Extending between these two pins is a link 40, said link being perforated near its ends to allow the pins 38 to pass through and the interiors of said portions are beveled or rounded as at 41. These rounded parts 41 are preferably placed in bushings as shown in Fig. 4. Surrounding the narrowed portion 42 of the pin 38 is a cylindrical collar 43 and surrounding said collar is a coil spring 44. The damper device can, if desired, be used with the springs 44 omitted as the spring 16 also dampens the movement of the bolster. The outer end of the pins 38 is threaded for the reception of a nut 45 and jam nut 46.

When the car is rounding a curve, the bolster swings transversely of the truck. The beveled or rounded portion of the perforations in the link 40 allows this link to move at an angle on the pins 38 as indicated in dotted lines in Fig. 4, and also restricts the side swing of the bolster, this side swing being restricted by the amount of bevel in the perforations. When this movement is taking place, the coil springs 44 on the pins 38 are being compressed and act to dampen or resist the movement of the bolster. The link 40 also prevents the bolster from coming into contact with the transoms and obviates the necessity of chafing plates.

It is obvious that my invention is not restricted to the embodiment shown, but is broad enough to cover all structures that come within the scope of the annexed claims.

What I claim is:

1. In a car truck of the class described, a truck frame, a bolster mounted within said frame, means for supporting said bolster and a link extending between the bolster and transom for preventing the bolster from coming into contact with the transoms.

2. In a car truck of the class described, a truck frame, transoms, a bolster mounted within said frame, means for supporting said bolster and means extending between the bolster and transoms and adapted to keep the bolster at a constant distance from the transoms and means for limiting the end movement of the bolster and preventing the

same from coming into contact with the side bars.

3. In a car truck of the class described, a truck frame, a bolster mounted within said frame, leaf springs and coil springs mounted between said leaf springs for supporting said bolster, a link extending between the bolster and the truck transom. 70

4. In a truck of the class described, a truck frame, a bolster mounted within said frame, leaf springs and coil springs mounted between the ends of said leaf springs for supporting the bolster, a pivot on the truck transom, a pivot on the bolster and a link extending between said pivots. 75

5. In a truck of the class described, a truck frame, a bolster mounted within said frame, leaf springs for supporting said bolster, spring seats at the ends of said leaf springs, coil springs extending between said 85 spring seats, laterally extending pivots on the bolster and truck transoms, a link extending between said pivots and means on said pivots for dampening the movement of the bolster. 90

6. In a truck of the class described, a truck frame, a bolster mounted within said frame, bolster supporting means comprising leaf springs, spring seats on said leaf springs, coil springs extending between said 95 spring seats and means on said spring seats adapted to come into contact when a predetermined load is imposed upon the truck, any further load being sustained by the leaf springs. 100

7. In a truck of the class described, a truck frame, a bolster mounted within said frame, leaf springs for supporting said bolster, spring seats at the ends of said leaf springs, coil springs mounted between said spring 105 seats, projections on said spring seats adapted to come into contact when a predetermined load is imposed upon the truck, any further load being carried by the leaf springs. 110

8. In a truck of the class described, a truck frame, a bolster mounted within said frame, leaf springs for supporting said bolster, spring seats at the ends of said leaf springs, coil springs extending between said spring 115 seats and between the leaf springs, projections on said spring seats, one projection surrounded by the other and adapted to come into contact with the opposite spring seat.

9. In a truck of the class described, a truck frame, a bolster mounted within said frame, leaf springs for supporting said bolster, spring seats on the ends of the leaf springs, coil springs mounted in said spring seats and extending between the leaf springs, projections on said spring seats, one of said projections surrounding the other projection, each of said projections being adapted to come into contact with the opposite spring seat when the coil springs are compressed. 120

10. In a truck of the class described, a truck frame, a bolster mounted within a frame, leaf springs for supporting said bolster, spring seats on the ends of said leaf springs, coil springs mounted between said spring seats and between the leaf springs, cylindrical projections on said spring seats, one of said projections moving within the other, each of said projections adapted to contact with the opposite spring seat when the coil springs are compressed. 45
11. In a truck of the class described, a truck frame, a bolster mounted within said frame, means for supporting said bolster, a link extending between the bolster and truck frame, said link preventing the bolster from coming into contact with the truck transoms and means adjacent to the ends of said link for imposing a frictional resistance to lateral swing of the bolster. 50
12. In a truck of the class described, a truck frame, a bolster mounted within said frame, means for supporting said bolster, a bearing on the bolster and a bearing on the truck frame, a link extending between the bolster and truck frame, means on said link for allowing a lateral swing of the bolster and means on said bearings for imposing a frictional resistance to said lateral swing of the bolster. 55
13. In a truck of the class described, a truck frame, a bolster mounted within said frame, means for supporting said bolster, a bearing on the bolster, a bearing on the truck transom, a link extending between said bearings, perforations in said link so formed as to allow a lateral movement of the bolster and springs on the bearings for imposing a frictional resistance to the lateral movement of the bolster. 60
14. In a truck of the class described, a truck frame, a bolster mounted within said frame, means for supporting said bolster, a bearing on the bolster, a bearing on one of the truck transoms, a link extending between said bearings and said bolster, a link extending between the bolster and truck frame, said link preventing the bolster from coming into contact with the truck transoms, perforations in said link, said perforations being interiorly rounded to allow a movement of the link on said bearings and springs bearing against said link and imposing a frictional resistance to the movement of said link. 65
15. In a truck of the class described, a truck frame, a bolster mounted within said frame, means for supporting said bolster, a bracket on the bolster, a bracket on the truck frame, pins mounted on said brackets, a link extending between said pins and having perforations into which said pins enter, said perforations being interiorly rounded to allow a movement of the link on said pins and springs on said pins for imposing a frictional resistance to the movement of said link. 70
16. In a truck of the class described, a truck frame, a bolster mounted within said frame, means for supporting said bolster, a bracket on the bolster, a bracket on the truck frame, perforations in said brackets, widened portions in said perforations, pins in said perforations, enlarged portions on said pins fitting the widened portions in the perforations, a link extending between said pins, perforations in said link through which said pins extend, said perforations being interiorly beveled to allow a movement of said link on said pins and springs on said pins for frictionally resisting the movement of said link. 75
